UNITED STATES PATENT OFFICE

TOM GORDON THRELKELD AND ARTHUR WILLIAM WRIGHT BUTTERFIELD, OF MANCHESTER, ENGLAND, ASSIGNORS TO RADIO CORPORATION OF AMERICA, A CORPORATION OF DELAWARE

AERIAL RECEIVING SYSTEM FOR WIRELESS SIGNALING

Application filed February 2, 1925, Serial No. 6,182, and in Great Britain February 6, 1924.

It is known that the reception of radio signals, especially the reception by amateurs of broadcast telephonic communications, is apt to be impaired by local electric disturbances due, for instance, to electric traction systems in the vicinity, electric elevators in the same or neighboring buildings, etc.

The object of this invention is to provide an aerial receiving system in which the effect of such local disturbances may be substantially obviated.

According to this invention we provide a wire or series of wires mounted parallel to and in proximity to the receiving aerial and grounded independently of the aerial, for instance, at the end opposite to that of the down-lead from the aerial.

The invention is illustrated in the accompanying drawings in which:

Fig. 1 shows an aerial equipped with our device and

Fig. 2 shows a modification thereof.

In Fig. 1 of the drawings *a* is the receiving aerial with the down-lead *b*, and *c c* are two wires mounted on each side of and parallel to the aerial *a*, and having their ends which are remote from the down-lead grounded.

Preferably the receiving aerial is provided with an earth mat or counterpoise (not shown).

Fig. 2 shows a modification in which several wires such as *c c* are employed, these being arranged along the edges of a prism along the axis of which the aerial *a* lies. Ground wires connected to these wires are also arranged along the edges of a prism, and the down-lead *b* from the receiving aerial extends along the axis of that prism.

Tuning and damping devices such as the inductance *d* and resistances *e e* may be inserted in the earthing wires.

Preferably the shielding wires *c c* are, as shown, longer than the aerial *a*.

Having described our invention what we claim is:—

1. In combination, an aerial for a receiving circuit, a plurality of conductors supported in parallelism to said aerial, grounded leads connected to said conductors, and adjustable impedances in said leads solely adjacent the

ground connections of said leads the impedance in at least one of said leads being purely resistive, the impedance in at least another of said leads including inductance.

2. In aerial receiving system means for shielding the antenna from local disturbance, which means consists of a plurality of conductors arranged about the antenna, each of said conductors being grounded and having connected with them respectively an adjustable impedance solely adjacent the ground connections the impedance in at least one conductor being purely resistive and the impedance in at least another conductor including inductance.

3. In combination, an antenna, two or more conductors supported in parallelism to said antenna, a grounded lead connected to each of said conductors, and an adjustable impedance in each lead solely adjacent the ground connection of the lead, the adjustable impedance in one lead being purely resistive, the adjustable impedance in another lead including inductance as well as resistance whereby the grounded leads will be given different characteristics so as to eliminate more than one type of interference.

TOM GORDON THRELKELD.

ARTHUR WILLIAM WRIGHT BUTTERFIELD.
